UNITED STATES PATENT OFFICE.

HENRY B. PURDY AND DENNIS S. BLUE, OF FREMONT, OHIO.

IMPROVEMENT IN STONE AND GLASS POLISHING MACHINES.

Specification forming part of Letters Patent No. **179,056**, dated June 20, 1876; application filed April 24, 1876.

To all whom it may concern:

Be it known that we, HENRY B. PURDY and DENNIS S. BLUE, of Fremont, in the county of Sandusky and in the State of Ohio, have invented certain new and useful Improvements in Machine for Rubbing and Polishing Stone and Marble; and do hereby declare that the following is a full, clear, and exact description thereof, reference being had to the accompanying drawings, and to the letters of reference marked thereon, making a part of this specification.

The nature of our invention consists in the construction and arrangement of a machine for rubbing and polishing marble or stone, as will be hereinafter more fully set forth.

In order to enable others skilled in the art to which our invention appertains to make and use the same, we will now proceed to describe its construction and operation, referring to the annexed drawings, in which—

Figures 1 and 2 are perspective views from opposite sides of the machine. Fig. 3 is a longitudinal section of the same. Fig. 4 is an enlarged vertical section of the sand-hopper. Fig. 5 is a bottom view of the rubber.

A represents the bed of the machine, across the center of which is erected a vertical frame, B, suitably braced on both sides. In suitable boxes at the upper end of the frame A is placed the horizontal driving-shaft C, which may be operated by hand or power, as desired. On this shaft is secured a beveled cog-wheel, D, which meshes with a beveled pinion, b, feathered on a vertical shaft, a. The upper end of the shaft a passes through a box, d, and plate e, between which the pinion b is placed. The shaft a passes loosely through a sleeve, f, which is provided with exterior screw-threads, and screws down through a nut, h, said nut, as well as the box d, being fastened to the front of the frame B. On the upper end of the hollow screw-sleeve h is secured a hand-wheel, E, which bears against the under side of a flange or collar, i, on the shaft a, and the lower end of said sleeve is swiveled in a coupling, k, attached to the shaft a. By this means the rubber G, connected to the lower end of the shaft a can be raised and lowered as required, and also rotated by the revolution of the main shaft C. The rubber-wheel G is made of cast-iron or other suitable material,

and provided on its upper surface with a cup or hopper, m, to receive and hold the sand and water, and in the bottom of this cup are holes, x, through which such sand and water pass to the under side of the rubber-wheel. From each hole x extends a groove, y, on the under side of the rubber-wheel, radially to the circumference, for the sand and water to work to the outer edge of said rubber-wheel. Through the lower end of the shaft a is passed a pin, p, the ends of which are inserted in slots in the cup m and are there held by keys n, so that the rubber-wheel will work freely upon the surface of the stone. The sand is contained in an elevated sand-box, H, from which it is fed through a spout, r, and pipe s to the cup m by means of a worm, I, run by a belt, t, from a pulley on the main shaft C. For regulating the flow of the sand, the speed of the worm I must be changed, which is done by passing the belt t over different-sized pulleys. The water to be used is pumped from a tank or cistern, J, into a keg or receptacle, K, by means of a pump, L, operated by a pitman, M, pivoted to a fly-wheel, N, on the end of the main driving-shaft C. From the receptacle K the water passes to the cup m through a pipe, w, and is regulated by a faucet or stop-cock, v. The pump L is arranged to pump up more water than is passed through the pipe w, so that the supply is kept up, and a waste-pipe, a', carries the overplus water back into the receptacle K, thereby keeping up a steady head. O is the carriage upon which the stone or marble to be dressed is laid. This carriage moves upon small wheels b', mounted within the bed A, and the carriage is guided in its movement backward and forward by means of a stationary rod, d', passing through plates e', secured on the ends of the carriage. On the under side of the carriage O is fastened a rack-bar, f', which meshes with a pinion, i', on a transverse shaft, h'. This shaft may be operated by hand by means of a lever P pivoted loosely on the shaft and provided with a spring-pawl, R, to take into a notched or cogged wheel, m', secured on the shaft so as to rotate said shaft in either direction, and hence move the carriage back and forth, as desired. Or this shaft may be operated from the main shaft C by cords or belts n' n', passing around

pulleys thereon, and around shifting-pulleys S S on the shaft h', said pulleys S S being shifted by a lever, V.

This machine is simple in construction and easily operated. For high polishing we use a rubber-wheel made of wood with felt fastened on the under side of the wheel.

Having thus fully described our invention, what we claim as new, and desire to secure by Letters Patent, is—

1. The combination of the rubber-wheel G, with the cup m, having slotted sides, the shaft a, pin p, and keys n n, substantially as and for the purposes herein set forth.

2. The combination of the sand-box H, worm I, spout r, pipe s, and cup m on the rubber-wheel G, substantially as and for the purposes herein set forth.

3. The combination of the tank or reservoir J, pump L, operated from the main shaft C, the barrel or receptacle K, pipe w, with faucet

v, and cup m on the rubber-wheel G, substantially as and for the purposes herein set forth.

4. The combination, with the rubber-wheel G and shaft a, of the hollow screw f, with wheel E, nut h, pinion b, and cog-wheel D on the main shaft C, all as and for the purposes herein set forth.

5. The combination of the carriage O, provided with perforated end plates e', the stationary guide-rod d', rollers b', rack-bar f', and pinion i', on the shaft h', substantially as and for the purposes herein set forth.

In testimony that we claim the foregoing we have hereunto set our hands and seals this 11th day of March, 1876.

HENRY B. PURDY. [L. S.]
DENNIS S. BLUE. [L. S.]
